DRIVING BOX EQUIPMENT

Homer Burton Baker, Baltimore, Md., assignor to
 The Balmar Corporation, Baltimore, Md., a corporation of Maryland

Application May 27, 1941, Serial No. 395,338

7 Claims. (Cl. 105—225)

This invention relates to the adjusting mechanism customarily employed in locomotive driving boxes, and is particularly concerned with the provision of improved means for substantially eliminating galling of the moving parts and thereby minimizing wear and increasing the useful life of the equipment. A typical mechanism of this kind is disclosed, in the United States Patent to Roberts No. 1,777,578 to which reference may be had if so desired for a very complete description of the manner in which these devices function.

The adjusting mechanism is installed at a side of the driving box between the box and the face of the adjacent pedestal jaw, which latter, of course, is a part of the locomotive frame. The box and the pedestal are generally constructed of steel, and since there is more or less constant relative motion between all of the parts there is a tendency toward galling and excessive wear between adjacent steel surfaces.

The present invention has for its primary object the provision of means for eliminating or at least greatly reducing the wear between adjacent steel surfaces. More specifically stated, it is the object of my invention to apply an anti-friction facing to at least one of two adjacent steel surfaces such, for example, as a facing of hard bronze or other suitable bearing metal.

In applying such facings certain difficulties have been encountered, to the overcoming of which the present invention is directed. For example, attempts have been made to apply a bronze facing either by directly casting the bronze or by flow-welding it against the surface of the steel. This procedure involves a considerable concentration of heat, and when used in applying the bronze either to the floating plate or to the compensating plate of the adjusting mechanism has resulted in warping of these plates so that excessive machining has been required to true-up the parts. In addition, it has been found that this procedure tends to develop a porous structure in the bronze which is highly undesirable. It has also been attempted to apply to the steel a pre-formed bronze plate which is secured in place by welding around the margins, but this procedure has resulted in considerable warping of the facings so that excessive machining is required, which of course is expensive not only in labor cost but also in waste of material.

It is the object of my invention to overcome these difficulties, and I accomplish my purpose in the following manner, reference being had to

the accompanying drawings which illustrate preferred practice.

Figure 1 is a partial side elevation of a locomotive driving box equipped with my improved adjusting mechanism;

5 Figure 2 is a section on an enlarged scale taken as indicated by the line 2—2 of Figure 1;

Figure 3 is an elevation of the pedestal face of the wedge; and

10 Figure 4 is a section taken as indicated by the line 4—4 on Figure 3.

In the drawings, the locomotive frame is shown at 5, and one of the pedestal jaws for the box 6, is illustrated at 7. The usual pedestal binder 8 fits across the bottom of the jaws.

15 The adjusting mechanism is installed between the box 6 and the jaw 7 and consists of a floating plate 9 and a wedge or compensating plate 10. The parts 6, 7 and 10 are usually constructed of steel and where two steel faces come together, as between the jaw 7 and the wedge 10, there is a tendency for the parts to gall or cut.

20 In applying my invention in practice I prefer to apply a bronze facing 11 to the pedestal side of the wedge or compensating plate 10. This facing is composed of a plurality of parts, preferably two, each of which is an individual longitudinally extending plate member 11a and 11b cut to the proper size and shape and ar-

25 ranged so as to provide a welding space 12 in the middle. I then weld these plates to the steel face of the wedge by means of welding applied at the margins, including the periphery 13 and the adjacent edges between the plates. In this 30 way I completely avoid any large concentration of heat with its coincident development of undue porosity and eliminate the troublesome warping hereinbefore mentioned. I also provide for the formation of a lubricant passage 15 which is drilled directly through the weld 14 between the adjacent edges of the plates 11a and 11b. By forming a passage through the weld a continuous channel is provided for the lubricant without the possibility of there being an 35 opening from this channel to the under face of the bronze facing between it and the steel of the wedge. This lubricant passage delivers into the Z-channel 16 on the pedestal face of the bronze. Lubricant is delivered through the connecting 40 passages 17 and 18 which are formed in an extension 19 at the upper end of one of the wedge flanges 20. Another passage 21 connects the 45 passage 18 with the hole 15 through the weld. Lubricant is delivered through the connecting 50 passages 17 and 18 which are formed in an extension 19 at the upper end of one of the wedge flanges 20. Another passage 21 connects the 55 passage 18 with the hole 15 through the weld.

While I have shown my bronze facing as being composed of two independent bronze plates mar-

ginally welded to the steel surface of the wedge, yet I wish it to be understood that the facing might be built up of more than two parts, although I have found this to be unnecessary in order to accomplish the object of the invention.

It should be understood, of course, that the invention can be employed in connection with any of the relatively moving surfaces involved in a driving box equipped with an adjusting mechanism. I have illustrated it as applied to the pedestal face of the wedge or compensating plate but if necessary or desirable it can be applied to the floating plate as well as to the faces of the jaws and of the box.

What I claim is:

1. A steel driving box wedge having a bronze facing composed of a plurality of plates marginally welded to the surface thereof and to one another, together with a lubricant passage formed through the weld between adjacent plate edges.

2. A steel driving box wedge having on its pedestal side a bearing metal facing, said facing being composed of a plurality of plates welded to the surface of the steel and to one another along their adjacent edges, and a lubricant passage formed through the weld between the edges.

3. A steel driving box wedge having on its pedestal side a bearing metal facing, said facing being composed of a plurality of plates marginally welded to the surface of the steel and to one another, together with a lubricant passage formed through the weld between adjacent plate edges.

4. A steel driving box wedge having on its

pedestal side a bearing metal facing, said facing being composed of a pair of substantially equal longitudinal plates welded to the surface of the steel and to each other along their adjacent edges, and a lubricant passage formed through the weld.

5. A plate of relatively hard metal for a driving box adjusting mechanism, said plate having a bearing facing composed of a plurality of strips of anti-friction metal of a length substantially equal to the length of said plate and of a width which leaves a relatively narrow space between adjacent strip edges while substantially covering said plate, said strips being marginally fused to the plate and to one another to provide a substantially continuous bearing surface.

6. The plate of claim 5 wherein a lubricant passage is formed through the fused material between adjacent strip edges.

7. An anti-friction bearing facing for a relatively movable and relatively hard surface in locomotive driving box equipment or the like, said facing being composed of a plurality of flat strips, the length and width of which strips being such as to provide an area which is substantially equal to said bearing surface less a relatively small space between the edges of adjacent strips, the strips being marginally fused to the hard surface and to one another to provide a substantially continuous bearing surface and the spacing between adjacent edges being sufficient to provide for a lubricating opening extending through the fused material.

HOMER BURTON BAKER.
